(57) **CLAIM**

I claim the ornamental design for a gun for a virtual reality system, as shown and described.

DESCRIPTION

FIG. 1 is a front perspective view of a gun for a virtual reality system according to the present design.

FIG. 2 is a front view of the gun for a virtual reality system of FIG. 1.

FIG. 3 is a rear view of the gun for a virtual reality system of FIG. 1.

FIG. 4 is a left side view of the gun for a virtual reality system of FIG. 1.

FIG. 5 is a right side view of the gun for a virtual reality system of FIG. 1.

FIG. 6 is a top view of the gun for a virtual reality system of FIG. 1; and,

FIG. 7 is a bottom view of the gun for a virtual reality system of FIG. 1.

The broken lines shown represent portions of the gun for a virtual reality system that form no part of the claimed design.
